Primary Examiner — Darlington Ly

(74) Attorney, Agent, or Firm — Michael S. Hargis

(57) **CLAIM**

The ornamental design for a cycle vehicle, as shown and described.

DESCRIPTION

FIG. 1 is a front and right side perspective view of a cycle vehicle, embodying my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a bottom plan view thereof;

FIG. 7 is a top plan view thereof;

FIG. 8 is a top plan view thereof with the seat bench in an alternate configuration;

FIG. 9 is a top, rear, and left side perspective view thereof; and,

FIG. 10 is a top, rear, and left side perspective view thereof with the seat bench removed.

The broken lines in the drawings illustrate portions of the cycle vehicle that form no part of the claimed design.
